UNITED STATES PATENT OFFICE.

WILLIAM H. ROSE, OF ST. JOHN'S, NEWFOUNDLAND, CANADA.

REPEATING-RIFLE BOLT ACTION.

Application filed June 19, 1924. Serial No. 721,029.

To all whom it may concern:

Be it known that I, WILLIAM H. ROSE, a subject of the King of Great Britain, residing at St. John's, Island of Newfoundland, have invented certain new and useful Improvements in Repeating-Rifle Bolt Actions; and I do hereby declare the following to be a full, clear, and exact description of the invention, such as will enable others skilled in the art to which it appertains to make and use the same.

The present invention relates to small firearms such as repeating or magazine rifles and deals more particularly with the bolt action and aims to provide means for automatically, or nearly so, unlocking the action, withdrawing the bolt, ejecting the empty cartridge, to provide means for closing, loading and locking the action without removing either hand from the rifle, or without taking the rifle from the shoulder or the eye from the sight, to provide safety means whereby the trigger is locked and prevented from being accidentally released until the action shall have been closed and locked and furthermore to provide means for preventing the firing pin touching the cartridge until the action is closed and locked.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a longitudinal sectional view of the lock, showing the bolt action embodying the invention and the relation of the parts when the action is closed.

Figure 2 is a sectional view on the line 2-2 of Figure 1,

Figure 3 is a view similar to Figure 1, showing the relation of the parts when the action is open,

Figure 4 is a sectional view on the line 4-4 of Figure 1, and

Figure 5 is a sectional view on the line 5-5 of Figure 1.

Corresponding and like parts are referred

to in the following description and designated in the several views of the drawings by like reference characters.

The breech bolt 1 is round and is slidable in the receiver 2 which engages the top and sides thereof. The bolt 1 is prevented from turning by means of a projection 3 of the locking lever 4, said projection entering a recess formed in the lower side of the bolt. A screw 5 threaded into an opening formed in a side of the receiver 2 has its inner end projecting into a longitudinal groove 6 formed in a side of the bolt 1, thereby further acting to prevent rotation of the breech bolt. This screw 5 also operates as an ejector for the empty shell. The locking bolt 7 is mounted to slide vertically in grooves formed in the sides of the receiver 2 and is adapted to fit squarely against the rear end of the breech bolt 1. The locking bolt 7 is approximately of U-form, as shown most clearly in Figure 4, and is provided with a cam 8 on the forward side of each member, said cam having its active face at an angle of about 60°.

The locking lever 4 operates in a slot 9 formed in the lower side of the receiver 2 and the projection 3 at its forward end normally extends into the groove formed in the lower side of the breech bolt 1. The locking lever 4 is pivoted at its forward end to the receiver 2 at 10, said pivot projecting beyond opposite sides of the locking lever and having the projecting ends entering longitudinal grooves 11 in which they have a free sliding movement when the lever 4 pivots. When the action is locked the rear end of the lever 4 is supported by a section 12 of the receiver 2. A link 13 is pivoted at one end to the rear portion of the locking lever 4, as indicated at 13^a, and is pivoted at its opposite end to the finger lever 14, as indicated at 13^b. The finger lever 14 is pivoted to an extension 15 of the trigger guard 100 15^a. The trigger 16 has a catch 17 associated therewith and to open the action the trigger 16 is pulled to the rear, thereby releasing the finger lever catch 17 thereby leaving the finger lever 14 free to drop to the position indicated in Figure 3. The catch 17 is adapted to engage stop shoulders 18 and 28 of the finger lever 14 and trigger 16, respectively, as shown most clearly in Figures 1 and 3. When the finger lever 110 catch 17 is released from its position at stop 18, the helical spring 19 mounted upon the

bolt 1 expands and the locking bolt 7 is forced downwardly by reason of extensions 21 at opposite sides of the collar 20 riding upon the inclines or cams 8 thereof. The locking bolt 7 bearing on the rear end of the locking lever 4 forces the latter downward and when it clears the abutment 22, it is free to ride upon the rearward incline 23 until it reaches the lower abutment 24, and at this time the breech bolt 1 reaches the limit of its rearward movement thereby ejecting the empty shell, provided the rifle has been fired, and a new cartridge is fed from the magazine into position ready to be placed into the chamber when the bolt 1 is moved forward.

To close the action, the hand engaging the grip of the rifle is closed thereby forcing the finger lever 14 upwardly and through the link 13 the locking lever 4 is returned to normal position and slides upon the incline 23 and engages the abutment 22, thereby pushing the bolt 1 forwardly and compressing the spring 19 and pushing the cartridge into the chamber. As the bolt 1 is moved forwardly, the cocking piece 25 engages the trigger sear 26 and is held back thereby. When the bolt 1 has reached its forward position, the locking lever 4 clears the upper end of the incline 23 and rises, thereby forcing the locking bolt 7 upward, and through the action of the cams or inclines 8 acting on the lugs 21 of the collar 20, forces said collar further ahead, thereby compressing the spring 19. When the locking lever 4 has reached the limit of its upward movement, the catch 17 engages the stop 18 of the finger lever and the action is fully locked and ready to be fired.

When the locking lever 4 reaches its lowest position, a projection 27 on the link 13 bears against the rear end of the finger lever catch 17—Fig. 3—forcing it downward and causing the opposite end of the catch to engage the trigger 16 which is thrown forward until the catch 17 clears the stop 28 which it engages, thereby holding the trigger 16 and allowing the sear 26 to rise high enough to hold back the cocking piece 25 when the bolt 1 goes ahead. The finger lever catch spring 29 tends to hold the catch 17 in position until the last motion of the finger lever 14 closing releases it. The stop shoulder 28 prevents the trigger 16 from being accidentally pulled before the action is fully closed. When the collar 20 comes to the rear lower part takes against a projection 30 on cocking piece 25 forcing the firing pin 31 to the rear assisted by the projection 3 on the forward end of the locking lever 4 bearing against the firing pin cap 32, thereby preventing the firing pin from touching the cartridge until the action is closed and locked.

It is observed that any type of box maga-

zine may be used, also any type of extractor, that illustrated forming no part of the invention. When action is open spring 19 does not fill space allotted to it. This enables the first closing movement to be easily effected. As bolt 1 goes forward the locking lever will become more nearly horizontal which gives greater leverage to overcome tension of the springs.

To remove bolt to clean the barrel first open the action; then with the left hand push the bolt forward until link 13 and locking lever rise high enough to allow rear end of catch 17 to rise by bearing on the forward end of same with the first finger of the right hand. Then with the thumb of the right hand force link 13 toward trigger guard 15^a, (squeezing catch and link together) at the same time pulling bolt to the rear with the left hand by the cocking piece 25. Rear end of locking lever 4 will then come down through slot through which link 13 works allowing forward pivoted end of lever 4 to drop down in rests 33 provided. Bolt now slips out of receiver. To replace bolt reverse operations. This is simple and quick in operation.

What is claimed is:

1. In a bolt action for a repeating rifle and in combination with the breech bolt, a locking bolt provided with a cam, and a collar or like member movable with the breech bolt and adapted to ride upon the said cam and move the locking bolt out of the path of the breech bolt. 100
2. In a bolt action for a repeating rifle and in combination with the breech bolt, a locking bolt, a member movable with the breech bolt and adapted to coat with the locking bolt to move the same out of the path of the breech bolt, and a locking member in cooperative relation with the locking bolt. 105
3. In a bolt action for a repeating rifle and in combination with the breech bolt, a locking lever having both a pivotal and a sliding connection with the receiver containing the breech bolt, a locking bolt adapted to be moved into operative position by means of the locking lever, and a member carried by the breech bolt and adapted to coat with the locking bolt. 110
4. In a bolt action for a repeating rifle, the combination of the breech bolt, a locking bolt provided with a cam, a member movable with the breech bolt and adapted to move the locking bolt into inoperative position, a locking lever having pivotal and sliding connection with the receiver containing the breech bolt and adapted to engage the locking bolt and move the same into operative position, a cocking member, and a sear in cooperative relation with the cocking member and trigger. 120
5. In a bolt action for a repeating rifle, 125

- and in combination with the breech bolt, a locking lever adapted to engage the breech bolt to prevent turning thereof and having both pivotal and sliding engagement 5 with the receiver containing the breech bolt, a finger lever, a link connection between the finger and locking levers, a trigger, and a catch adapted to engage both the trigger, the said link and the finger lever.
- 10 6. In a bolt action for a repeating rifle, the combination of a breech bolt, a locking bolt having a cam, a member movable with the breech bolt and adapted to engage the locking bolt, a locking lever adapted to engage the breech bolt and having pivotal and sliding engagement with the receiver containing the breech bolt, a finger lever, a link connecting the finger and locking levers, a cocking member, a sear and a catch 15 adapted to cooperate with the trigger, link and finger lever.
- 20 7. In a bolt action for a repeating rifle,
- 25 a helical spring associated with the bolt, locking means for holding the bolt projected and the helical spring compressed, and 25 means for tripping the said locking means whereby the helical spring operates to effect automatic unlocking of the action and a withdrawing of the bolt.
- 30 8. In a repeating rifle, the finger lever for actuating the loading mechanism located in the grip of the rifle for actuation by the hand engaging the grip.
- 35 9. In a bolt action for a repeating rifle, a bolt, a helical spring associated therewith, 35 a collar slidably mounted on the bolt and engaging said spring, a locking bolt to hold the first mentioned bolt in firing position, and a cam face on said locking bolt adapted to engage said collar.

40 In testimony whereof I affix my signature.

WILLIAM H. ROSE.
